DESIGN FOR FABRIC FOR SHOE UPPERS

Harry Aull, Philadelphia, Pa., assignor to Fried-berger-Aaron Manufacturing Company, Philadelphia, Pa., a corporation of Pennsylvania

Application January 5, 1938, Serial No. 74,102

Term of patent 7 years

To all whom it may concern:

Be it known that I, Harry Aull, a citizen of the United States, residing in Philadelphia, county of Philadelphia, State of Pennsylvania, have invented a new, original, and ornamental Design for Fabric for Shoe Uppers, of which the following is a specification, reference being had to the accompanying drawing, which forms a part thereof.

Figs. 1 and 2 are views of opposite faces of a fabric embodying my design.

I claim:

The ornamental design for fabric for shoe uppers, as shown.

HARRY AULL.
